UNITED STATES PATENT OFFICE

HELMUT JUNGHANS, OF SCHRAMBERG, GERMANY, ASSIGNOR TO SOCIETA ANONIMA
ARTURO JUNGHANS FABRICA D'OROLOGERIA, OF VENICE, ITALY

MECHANICAL TIME FUSE FOR ARTILLERY PROJECTILES

Application filed July 30, 1931, Serial No. 554,101, and in Germany August 15, 1930.

The present invention relates to mechanical time fuses for artillery projectiles and more particularly to a time fuse of the stated kind wherein the necessary moments of force 5 are obtained exclusively by means of centrifugal weights.

In fuses of this type as hitherto constructed the driving toothed segments or racks are adapted to mesh directly with a pinion keyed 10 to or integral with the central shaft of the fuse, said shaft carrying the usual setting disk and being arranged to perform a single revolution only during the most prolonged trajectory or flight of the projectile, whereas 15 according to the present invention, a means for transmission from a lower to a higher speed is interposed between the said segments and the central shaft, said means comprising a system or set of toothed wheels. 20 The provision of such a transmission means between the driving segments loaded with centrifugal weights, and the central shaft of the fuse entails a marked advantage over the time fuses of this type as hitherto constructed 25 or suggested, inasmuch as the said centrifugal weights will have to travel a path of minimal length only in order to cause the central shaft to move and perform a full revolution. In this way the difference in the positions of the 30 centrifugal weights relative to the revolution axis, at the commencement and at the end of the movement will be but small only, while the centrifugal force which apparently is the driving force of the fuse, will increase 35 in accordance with the increase of the distance between the centrifugal weights and the rotation axis.

Thus the reduction of the path or travel of the segments will act to obviate and decrease 40 the unevenness or disproportion of the driving force during the flight of the projectile. Said unevenness, disproportion or increase of force is approximately proportionate to the decrease of the rotation speed of the projectile during the flight, so that the driving force will be approximately the same or alike during the whole duration of the flight.

The objects and advantages of the invention will be obvious from the following description of an embodiment thereof, read in

connection with the accompanying drawings, forming a part of this specification and showing somewhat diagrammatically for purposes of exemplification, a preferred form and manner in which the invention may be embodied and practised, but without limiting the claimed invention to such illustrative instance:

Figure 1 is a rear view partly in section of the fuse, and

Figs. 2 to 5 are graphic representations indicating the calculations of the centrifugal forces.

The two centrifugal weights *a* are firmly attached to toothed segments *a'* pivotally mounted on supporting studs *b* so as to be adapted to turn thereabout. The two segments *a'* engage in pinions *c* firmly connected or integrally formed with toothed wheels *d* constituting the means for transmission 65 from a lower to a higher speed, between the segments *a'* and the central shaft *e*, the arrangement being such that both wheels *d* engage at diametrical points in a pinion keyed to or integral with the shaft *e* and adapted 70 to actuate in a known manner both the setting disk *f* and regulating means of the fuse. 75

Figures 2 to 5 of the drawings illustrate graphically two calculations of the driving centrifugal forces, Figure 2 showing the calculation of the driving centrifugal forces of the prior construction, wherein the segment immediately engages in the pinion of the central shaft. In this case the weight appended to the segment will travel a path of 80 85 10 mm length at or for a full revolution of the central shaft.

Apart from the centrifugal forces acting upon the weight of the segment, the tangential forces are plotted and converted to the 90 pitch circle of the pinion of the central shaft. Figure 4 is a diagram showing the said tangential forces in the form of a curve. It will be seen therefrom, that the force at the beginning of the movement bears a proportion of 1 to 3, 4 to the force exerted at the end of the movement.

Figure 3 illustrates the same graphical calculation or plotting respecting the construction of the fuse according to the present in- 100

vention, wherein the segments do not immediately mesh with the pinion of the central shaft but rather engage in a separate pinion formed integral with a toothed wheel meshing with the pinion of the shaft. In this way, that is due to the transmission means provided in my fuse, the movement or travel of the weights will amount to 3, 5 mm. only, while the movement of the central shaft, that 10 is one revolution in case of a most prolonged flight or trajectory, will be the same. In Figure 3 the tangential forces at the center of gravity of the segment likewise are plotted from the centrifugal forces by division and 15 the said forces are correlated to the pitch circle of the pinion of the central shaft with consideration of the transmission effected in this case.

The tangential forces are similarly shown 20 in Figure 5 in the form of a diagram from which will be seen that the force at the commencement of the movement bears a relation of 3 to 4 to the force prevailing at the end of the movement. Since, as hereinbefore 25 mentioned, the rotating speed of the projectile decreases during the flight approximately in the same ratio, an approximately uniform driving force is likely to prevail at such a proportion or condition of the forces 30 during the entire flight or trajectory.

From the foregoing it is believed, that the advantages and novel features of my invention will be readily understood, and, there-

fore, further detail description is deemed unnecessary. I desire, however, to emphasize the fact that various minor changes in the details of construction and in the proportion of parts may be resorted to when required, without sacrificing any of the advantages of my invention as defined in the appended claims. 70

What I claim is:—

1. In a time fuse for artillery projectiles 75 having a setting disk, comprising toothed segments, centrifugal weights firmly associated with the said segments, a central shaft, and transmission means interposed between the said segments and the said shaft.
2. In a time fuse for artillery projectiles having a setting disk, comprising two pivotally mounted toothed segments, centrifugal weights associated with the said segments, a central shaft, and a spur gear system interposed between the said segments and the shaft. 85
3. In a time fuse for artillery projectiles having a setting disk, comprising two pivotally mounted toothed segments, centrifugal 90 weights associated with the said segments, a central shaft, a pinion keyed to the shaft, a pair of spur gears meshing with the said pinion, and a pair of pinions associated with the said two spur gears, respectively, and engaging 95 in the said two segments, respectively.

In testimony whereof I affix my signature.
HELMUT JUNGHANS.
